(57) **CLAIM**

The ornamental design for a foldable shovel, as shown and described.

DESCRIPTION

FIG. 1 is a perspective view of a foldable shovel showing our new design, shown in its fully unfolded configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partial enlarged view of the indicated area “8” in FIG. 1;

FIG. 9 is a partial enlarged view of the indicated area “9” in FIG. 1;

FIG. 10 is a perspective view thereof, wherein a handle of the foldable shovel is shrunk; and,

FIG. 11 is a perspective view thereof, shown in a folded configuration.

The broken lines shown in the drawings depict portions of a foldable shovel that form no part of the claimed design. The symbolic dash-dot-dash lines shown in FIG. 1 is for the purpose of mapping the enlargements of FIGS. 8 and 9 and form no part of the claimed design. The dash-dot dash line in FIGS. 8 and 9 are for the purpose of indicating the bounds of the enlargement and form no part of the claimed design.
